UNITED STATES PATENT OFFICE.

OSCAR HARVEY GREENE, OF CHICO, CALIFORNIA:

DESIGN FOR A SIDE-WALL WRITING-CASE.

SPECIFICATION forming part of Design No. 31,312, dated August 1, 1899.

Application filed July 5, 1899. Serial No. 722,875. Term of patent 14 years.

To all whom it may concern:

Be it known that I, OSCAR HARVEY GREENE, a citizen of the United States, residing at Chico, in the county of Butte and State of California, have invented and produced a certain new and original Design for Side-Wall Writing-Cases; and I do declare the following to be a full, clear, and exact description of the invention, such as will enable others skilled in the art to which it appertains to make and use the same.

The invention relates to a new and original design for a side-wall writing-case; and it consists of the design shown in the accompanying drawings, in which—

Figure 1 is a plan view of the invention. Fig. 2 is a vertical sectional view on the line $y y$, and Fig. 3 is a transverse sectional view on the line $x x$.
20 In the drawings, 1 denotes the base of the writing-case, which is rectangular in form and is provided with a pocket 3, upon which is arranged the pocket 4 and at the sides of which are vertically-disposed receptacles 5. 25 Below these pockets 3 and 4 are arranged pockets or receptacles 6, 7, and 9 and a space

8, and below the receptacles 6 and in line therewith are arranged hooks 10 and 12, and arranged between these hooks 10 and 12 is a hook 11.

30 The pocket 3 is adapted to contain writing-paper; the pocket 4, envelopes; the pockets 5, penholders or pencils; the pockets 6, the ink-holders; the pocket 7, stamps; the space 8, a calendar, and the pocket 9 pen-points. 35

The hooks 10 are adapted to hold a ruler, the hook 11 a pen-wiper, and the hook 12 letters or receipts.

The device is exceedingly useful and may be made for office or commercial purposes or 40 may be adapted to the wants of school-children.

What I claim is—

The design for a side-wall writing-case, as 45 herein shown and described.

In testimony whereof I have hereunto set my hand in presence of two subscribing witnesses.

OSCAR HARVEY GREENE.
